UNITED STATES PATENT OFFICE.

HARRY ASHER, OF LONDON, ENGLAND.

DETACHABLE HEEL FOR BOOTS AND SHOES.

Application filed August 17, 1927, Serial No 213,593, and in Great Britain April 9, 1927.

This invention relates to boots and shoes of the type in which a metal base or holder plate secured to the heel lift, sole or other permanent part of the boot or shoe is provided upon or in its under face with ribs or slots of dovetail or equivalent form adapted to be engaged by corresponding slots or ribs in or upon a detachable heel, sole or other wearing part which is applied in position by sliding longitudinally with respect to the ribs or slots.

The present invention has among its objects to provide an improved and an effective construction of such boots and shoes, whereby the replacement or renewal of the detachable heel or sole may be facilitated and whereby the heel or sole may be fixed in the position of use without the necessary use of any tools.

In known constructions of boots and shoes of the type referred to, the normal position of the detachable heel or sole has been determined by suitably shaping or positioning the dovetail or equivalent interlocking ribs and slots. It has also been proposed to provide a heel with a metal plate having a short downwardly extending grooved part at each side at the front part of the heel, with which grooved parts a leather pad or wearing part is adapted to engage slidably, the front ends of the grooved parts being connected by a downwardly extending ridge against which the front part of the pad or wearing part abuts and the latter being fixed in position by means disposed at the rear part of the heel.

According to the invention, in a boot or shoe of the type specified, the base or holder plate is provided with a downwardly extending flange by which the normal position of the detachable heel or sole is determined and which co-operates with means upon the detachable heel or sole for preventing the latter detachable heel or sole from sliding out of position. The flange may extend the whole depth or thickness of the detachable heel or sole.

According to the invention, moreover, in order to fix the detachable heel or sole in its normal position of use, that is, in the position in which it abuts against the downwardly extending flange of the base or holder plate and thus to prevent longitudinal or other sliding movement of the detachable heel or sole with respect to the boot or shoe when in use, fixing means such for instance as a sheet metal tag or tags or the equivalent may be

provided to extend from the part of the detachable heel or sole which causes to lie against or adjacent to the downwardly extending flange aforesaid and to pass through a slot or slots provided for the purpose in the downwardly extending flange, the tag or tags or the equivalent being adapted easily to be bent into a position to engage with or against the outer face of the flange. 60

According to the invention, moreover, means may be provided to facilitate the removal of the heel or sole when it becomes worn. Thus one or more holes or recesses may be provided in the downwardly extending flange hereinbefore referred to so that on the sheet metal tag or tags or the equivalent being straightened out to permit their withdrawal from the corresponding slot or slots in the downwardly extending flange, a punch 70 or other tool may be applied through the holes or recesses in the flange to drive off the detachable heel or sole. The slot or slots or the equivalent may be enlarged or flared outwardly at their outer end, or the rib or ribs which engage therewith may be tapered or otherwise reduced in cross-section at the respective end so that thus the location of the interlocking parts in position to be engaged by the sliding heel or sole longitudinally or otherwise with respect to the boot or sole may be facilitated. 80

The invention further comprises the features hereinafter described.

The invention is hereinafter described with reference to the accompanying diagrammatic drawing, in which:—

Figure 1 is a part sectional side elevation of the rear part of a shoe provided with a detachable heel according to the invention; 90 the detachable heel being shown in a position in which it is partly applied upon the shoe;

Figure 2 is a side elevation showing the detachable heel in the position of use upon the 100 shoe;

Figure 3 is a top plan view of the detachable heel;

Figure 4 is a rear elevation of the shoe with the detachable heel removed, and 105

Figure 5 is a cross-section corresponding to Figure 3.

In carrying the invention into effect according to one construction and with reference to the accompanying diagrammatic drawing, the heel lift *a* is provided on its undersurface with a metal base plate *b* secured

- in position by means such as nails or screws. A pair or parallel longitudinally extending ribs or bars *c* conveniently of metal, may be fixed upon the undersurface of the base plate *b*, for example by soldering, the ribs or bars *c* being of a dovetail or other suitable cross-section adapted to engage and to interlock with corresponding undercut slots *d'* or recesses in the detachable heel *d*. The ribs or bars *c* advantageously extend short of the rear of the heel and the slots *d'* or recesses in the heel *d* may be substantially co-extensive so that thus the rear part of the heel presents an unbroken contour.
- 15 As shown in Figure 1, the detachable heel *d* is applied in position by sliding longitudinally towards the toe of the shoe, the position of use being determined, by means of a flange *b'* extending downwardly from the base plate *b* at the front end thereof. Sheet metal tags *e* or the equivalent may be provided upon the detachable heel *d* advantageously flush with the upper surface thereof, the tags *e* or the equivalent being adapted to extend through corresponding slots *b²* in the flange *b'* of the base plate *b*, and (as shown in Figure 2) being turned or bent upwardly or downwardly to engage with or against the outer or front face of the flange *b'*. By such means it will be understood that the detachable heel may be held firmly in position during wear.
- When it is desired to remove the detachable heel *d* for the purpose of replacement or renewal, the tags *e* are straightened out to permit their withdrawal from the slot *b²* in the flange *b'* and in order to facilitate the removal of the heel *d* by sliding rearwardly holes *b³* may be provided in the flange *b'* in suitable positions whereby a punch or other tool 40 may be applied against the front part of the heel *d* to drive the latter off. Furthermore, in order to facilitate the application of the heel into position, the slots *d'* in the heel *d* may be enlarged or flared outwardly at the front end, as indicated in Figure 3.
- The tags *e* may be secured to the heel *d* by providing them at their rear part with downwardly extending serrated flanges *e'* or the like which are driven into the leather or other material of which the upper part of the heel *d* is made. The heel *d* may be made in one piece of leather, rubber, metal or other suitable material, or, as shown in the drawings,

may be made of two or more superimposed layers nailed or otherwise secured together to form an integral part. 55

It will be understood that the invention is not limited to the construction hereinbefore described. For example, the downwardly extending flange *b'* of the base plate *b* may be provided at the rear or at the rear and sides and may be curved or shaped to the contour of the heel, in which case the heel *d* is applied in position by sliding rearwardly. Furthermore, the tags *e* may be otherwise disposed and may be adapted to be bent laterally to engage with or against the outer or front face of the flange *b'*; while in place of providing the ribs or bars *c* upon the heel lift or other corresponding part, they may be provided upon the detachable heel, the undercut slots being provided in the heel lift. 60 65 70

In a slightly modified construction, the base plate *b* may be slightly smaller than the lift *a* and may be recessed therein so as to leave an upstanding non-metallic margin and thus to avoid the appearance of any metal at the sides or rear of the heel and to provide only a simple line joint between the parts *a* and *d*. 75

It will be obvious that the present invention is applicable to the soles of boots and shoes as well as to the heels thereof as particularly described. 80

What I claim is:—

85 A shoe heel having upper and lower sections, a plate secured against the under face of the upper heel section and having a depending portion at its front edge constituting an abutment and formed with an opening, a longitudinally extending rib depending from the plate between the abutment and the rear end of the plate and dovetailed in cross section, the lower heel section having a longitudinally extending groove opening through its front edge face and dovetailed in cross section to snugly receive the rib, and a fastener 90 having an attaching portion secured against the upper face of the lower heel section and a tongue projecting forwardly and passed through the opening in said abutment and bent into clinching engagement with the front face thereof. 95 100

In testimony whereof I have hereunto signed my name.

HARRY ASHER.
